UNITED STATES PATENT OFFICE.

HARLEY M. DUNLAP AND DELMER M. PUTNAM, OF BATTLE CREEK, MICHIGAN.

MOTOR MOUNTING.

Application filed February 23, 1924. Serial No. 694,802.

To all whom it may concern:

Be it known that we, HARLEY M. DUNLAP and DELMER M. PUTNAM, citizens of United States, residing at Battle Creek, county of Calhoun, State of Michigan, have invented certain new and useful Improvements in Motor Mountings, of which the following is a specification.

This invention relates to improvements in 10 motor mountings.

We have illustrated our improvements as we have adapted the same for air pumping units, although our improvements may be adapted and are desirable for use in other 15 relations.

The main object of this invention is to provide an improved motor mounting which serves as a means for maintaining desired driving tension upon the belt.

20 Objects pertaining to details and economies of construction and operation of our invention will definitely appear from the detailed description to follow.

We accomplish the objects of our invention 25 by the devices and means described in the following specification. The invention is clearly defined and pointed out in the claims.

A structure which is a preferred embodiment of our invention is clearly illustrated 30 in the accompanying drawing forming a part of this application, in which:

Fig. I is a side elevation of an air pump unit embodying the features of our invention.

Fig. II is a fragmentary plan view.

Fig. III is a detail section on a line corresponding to line 3—3 of Fig. II, looking in the direction of the arrows.

40 In the drawing similar reference numerals indicate similar parts in all of the views.

Referring to the drawing, the base 1 is a casting of desired dimensions to support the parts mounted thereon. 2 is an air pump provided with a driven pulley 3. This air pump is mounted at one end of the base. On the other end of the base we mount a motor 4 having a driving pulley 5 connected to the pulley 3 by the belt 6. These parts 50 are conventionally shown.

The motor 4 is slidably supported by means of the slide bracket 7 having spaced ears 8 slidably engaging the rod 9 mounted on the base. A supporting shoe 10 supports

the other end of the motor, this shoe sliding 55 upon the base.

The rod 9 is arranged parallel with the belt 6 so that the motor slides in a plane parallel with the belt. The ears 8 are substantially spaced and the shoe 10 is of such 60 length and shape that a three-point support is provided for the motor.

A coiled spring 11 is connected to the lug 12 on the forward ear 8 and the other end to lug 13 on one of the rod supporting 65 brackets 14.

By thus arranging the parts the motor is supported so that it is substantially free from racking strain, owing to the pull of the belt, and the desired tension is maintained 70 upon the belt. This is of particular importance in air pumps and the like where there is a substantial variation in the load, the load increasing as the pressure under which the pump is working increases.

75 Our arrangements are, however, desirable for use in a great variety of relations as we provide means by which the proper belt tension between a motor and a driven machine is automatically maintained without use of a belt idler and notwithstanding the stretching of the belt which occurs to a greater or less extent. The stretching being automatically taken up there is no necessity for adjusting the motor to compensate for such stretching.

80 It has been quite general practice to provide for adjusting the motor to take up the stretch of the belt but this is frequently neglected resulting in the tension being reduced to such an extent that slippage occurs, frequently resulting in burning of the belt.

85 In addition to the advantage of the automatic adjustment no lubrication is required as is occasioned by a belt tightening idler.

Having thus described our invention what we claim as new and desire to secure by Letters Patent is:

1. In a structure of the class described, 100 the combination of a base, a driven unit mounted on said base and provided with a pulley, a motor provided with a driving pulley, a belt connecting said pulleys, a motor supporting slide rod disposed on said base parallel with said belt and below said driving pulley, a motor supporting bracket having substantially spaced ears slidably en-

- gaging said rod, a coacting supporting shoe for said motor, said shoe being freely movable on said base as guided by said slide rod, said supporting shoe being adapted to engage the base between the vertical planes of said bracket ears whereby a three-point support is provided for the motor, and a spring connected to said motor and to said base whereby tension is applied to said belt.
5. In a structure of the class described, the combination of a base, a motor provided with a driving pulley, a motor supporting slide rod disposed on said base parallel with said belt and below said driving pulley, a motor supporting bracket having substantially spaced ears slidably engaging said rod, and a coacting supporting shoe for said motor, said shoe being freely movable on said base as guided by said slide rod, said supporting shoe being adapted to engage the base between the vertical planes of said bracket ears whereby a three-point support is provided for the motor.
6. In a structure of the class described, the combination of a base, a motor provided with a driving pulley, a driving belt, a slide rod mounted on said base, a supporting bracket for the pulley end of said motor slidable on said rod, a supporting shoe for the other end of said motor, said shoe being freely movable on said base as guided by said slide rod, and a belt tightening spring connected to said slide and to said base.
7. In a structure of the class described, the combination of a base, a motor provided with a driving pulley, a driving belt, a support for said motor comprising a shoe disposed at one end of the motor and slidable on said base, a slide rod disposed at the other end of the motor and transversely of the axis of its pulley, said shoe being freely movable on said base as guided by said slide rod, and a motor supporting slide coacting with said rod, a motor supporting slide coacting with said rod, and a spring connected to said motor and base, for the purpose specified.
8. In a structure of the class described, the combination of a base, a motor, a support for said motor comprising a shoe disposed at one end of the motor and slidable on said base, a slide rod disposed at the other end of the motor and transversely of the axis of its pulley, said shoe being freely movable on said base as guided by said slide rod, and a motor supporting slide coacting with said rod.
9. In a structure of the class described, the combination of a motor provided with a driving pulley, a driven pulley, a belt connecting said pulleys, a slide rod disposed in a plane parallel to said belt, a motor supporting bracket slidably engaging said rod, a coacting supporting shoe for said motor, said shoe being freely movable on said base as guided by said slide rod, and a spring connected to said motor for yieldingly supporting it on said rod to tension said belt.
10. In a structure of the class described, the combination of a motor provided with a driving pulley, a driven pulley, a belt connecting said pulleys, a motor supporting slide rod disposed parallel with said belt and below said driving pulley, a motor supporting bracket having substantially spaced ears slidably engaging said rod, a coacting supporting shoe for said motor, said shoe being freely movable on said base as guided by said slide rod, and a spring connected to said motor whereby tension is applied to said belt.
11. In witness whereof, we have hereunto set our hands.

HARLEY M. DUNLAP.
DELMER M. PUTNAM.
